UNITED STATES PATENT OFFICE.

EZRA G. CLYMAN AND ANDREW M. HESS, OF WAYNESBORO, PENNSYLVANIA, ASSIGNEES
TO THE GEISER MANUFACTURING COMPANY, OF WAYNESBORO, PENNSYLVANIA.

STRAW-STACKER.

No. 901,884.

Specification of Letters Patent.

Patented Oct. 20, 1908.

Application filed April 11, 1908. Serial No. 426,608.

To all whom it may concern:

Be it known that we, EZRA G. CLYMAN AND ANDREW M. HESS, residing at Waynesboro, in the county of Franklin and State of Pennsylvania, have invented certain new and useful Improvements in Straw-Stackers; and we do hereby declare the following to be a full, clear, and exact description of the invention, such as will enable others skilled in the art to which it appertains to make and use the same.

This invention relates to straw-stackers used in connection with threshing-machines; and it consists in the novel construction and combination of the parts hereinafter fully described and claimed whereby the straw-stackers is made telescopic and whereby the straw is guided at its lower end.

In the drawings, Figure 1 is a side view showing an outline of the principal parts of the straw-stackers. Fig. 2 is a side view of one of the guards of the lower end of the elevator, drawn to a larger scale. Fig. 3 is a plan view of the said guard. Fig. 4 is a side view of the driving devices for the telescopic upper section of the straw-stackers, drawn to a larger scale. Fig. 5 is a partial plan view of the same. Fig. 6 is a cross-section through the upper section of the straw-elevator, taken on the line $x-x$ in Fig. 5.

A is a portion of the frame of a horizontal straw-conveyer provided with an endless carrier B of approved construction. This straw-conveyer is provided with a driving-shaft a' , and has the rear end portion b of its carrier arranged at an angle to the main portion of the said carrier and supported by suitable pulleys or rollers b' .

C is the lower section of a straw-elevator provided with brackets c at its lower end, which brackets are pivoted to the frame A concentric with the shaft a' .

D is the straw-elevator carrier formed of an endless apron and provided with suitable cross-slats. The lower end portion of this carrier D passes over flanged pulleys E secured upon a driving-shaft d which is journaled in the brackets c .

The straw-elevator section C is trough-shaped in cross-section, and it is preferably provided with a metallic bottom plate c' . The straw is delivered by the straw-conveyer between the bottom plate c' and the

lower bight of the carrier D which is driven in the direction of the arrows. Any approved driving mechanism is used, and the above-mentioned parts and their driving mechanism are preferably the same as fully described in the application of E. G. Clymans and M. A. Flautt, filed Jan. 23, 1908, Serial Number 412,301.

In order to assure the delivery of all the straw to the straw-elevator in a satisfactory manner, guard-plates F are secured at the lower end of the straw-elevator. These guard-plates are similar to each other. Each guard-plate is arranged adjacent to the flanged end of one of the pulleys E, and is provided with a laterally projecting flange f which overlaps the flange of the pulley. The guard-plate is provided with a hub f' which is secured to the bearing in which the driving-shaft d is journaled, and it is also provided with a curved arm e which is bolted to the straw-elevator side-bar. The hub f' projects laterally of the plate F and on the same side thereof as the flange f , and the inner edge of the flange comes flush with the inner edge of the pulley flange, as shown in Fig. 3, so that the carrier is effective at this point for its full width. The flat portion of the guard-plate is arranged to the rear of the shaft d , and it and its flange f prevent the straw from catching and accumulating at this point, and also from being thrown out sidewise.

The lower section C of the elevator is preferably provided with a hinge G at its middle part so that it can be folded up, and g is a hook or other similar catch for holding the parts of the lower section in line with each other. Guide pulleys g' are carried by the lower section C for holding the upper bight of the carrier D clear of the lower bight.

H is the upper and slideable section of the straw-elevator. The sides of this upper section straddle the sides of the lower section, and it is preferably provided with a bottom-plate h of metal which slides under the bottom-plate c' of the lower section.

I is a roller provided with a shaft i which is journaled in the upper end portion of the upper section H, and which supports the upper end of the elevator carrier.

J are arch-shaped brackets secured to the upper end portion of the lower section C and

overlapping the sides of the upper section H. J' is a crosspiece between the free end portions of the said brackets.

5 K are brackets secured to the middle part of the lower section C. The brackets J are provided with clamps j, and the brackets K are provided with similar split clamps k.

L is a tubular guide secured in the clamps j and k at each side of the elevator and arranged parallel with each other and with the 10 sections of the straw-elevator.

M are rollers mounted on pins m, and carried by arms m' which project from the brackets J. The side-bars of the upper section 15 H run upon the rollers M.

N are slides secured to the lower end portion of the upper section H, and n are anti-friction rollers journaled in the said slides and running on the guides L.

20 O are sprocket-wheels journaled on pins which project from the brackets J, and P are sprocket-wheels secured on a shaft R which is journaled in the brackets K. Drive-chains p of any approved construction pass 25 over the wheels O and P, and have their lower bights arranged in the tubular guides L.

One end of each drive-chain is secured to 30 one of the slides N, and its other end is secured to an arm p' which projects from the upper section H. One end of each drive-chain is provided with a tightening-device such as an adjustable eye-bolt. The shaft R extends across the straw-elevator, and it is 35 provided with a crank-handle r on one end.

S is a check-pawl pivoted to the lower section C and engaging with one of the drive-chains so that the upper section cannot slide down by gravity.

40 T is a portion of the stay which supports the straw-elevator at any desired angle, and which is connected to the upper end portion of the lower section.

U is a clamp for holding the elevator carrier in place when the elevator is folded up. 45 Four of these clamps are provided, two being arranged on each side of the elevator. Each clamp consists of a cranked bar provided at one end with an arm u which is revoluble 50 and slidable longitudinally in a socket V secured to the side of the elevator. A set-screw w is provided for securing the arm in the socket. When the elevator is folded back onto the top of the threshing-machine,

55 the arm is slid upward in its socket and is turned around so that the cranked bar can be pressed down onto the carrier in the trough of the elevator. The clamp is secured by the set-screw so as to clamp the carrier against the bottom-plate. The upper 60 slideable section is moved in and out as occasion requires by revolving the crank-handle r. The elevator carrier is made in sections which are secured together so that they can 65 easily be separated, and one or more of these

sections are removed or added to suit the extension of the slideable section of the elevator. This telescopic straw-stacker is specially adapted for use in barns as it enables the straw to be deposited in different parts of the barn without moving the threshing-machine. The tubular guides protect the lower bights of the drive-chains from injury, and prevent straw from catching in them.

What we claim is:

1. In a straw - stacker, the combination, with an inclined straw-elevator provided with an endless carrier and having shaft bearings at its lower end, of a driving shaft journaled in the said bearings and provided with flanged pulleys for driving the said carrier, and guard-plates provided with laterally projecting flanges which overlap the flanges of the said pulleys and having also hubs which project laterally from them on the same side as the said flanges and which are secured on the said bearings.

2. In a straw - stacker, the combination, with a straw-elevator formed of hinged sections and provided with an endless carrier, of a socket secured to one of the said sections, a clamp for the said carrier comprising a cranked bar which is slideable and revoluble in the said socket, and means for securing the said bar to the said socket.

3. In a straw - stacker, the combination, with a straw - elevator provided with an upper telescopic section, of a tubular guide secured to the lower section of the said elevator, wheels carried by the said lower section, a flexible connection passing over the said wheels and secured to the said telescopic section and having its lower bight arranged in the said tubular guide, and a slide secured to the lower part of the said telescopic section and working on the said guide.

4. In a straw - stacker, the combination, with a straw - elevator provided with an upper telescopic section, of a tubular guide secured to the lower section of the said elevator, sprocket-wheels carried by the said lower section, a drive-chain engaging with the said sprocket-wheels and secured to the said telescopic section and having its lower bight arranged in the said tubular guide, a slide secured to the said telescopic section and working on the said guide, and a driving device for revolving one of the said sprocket-wheels.

5. In a straw - stacker, the combination, with a straw - elevator provided with an upper telescopic section which slides outside of its lower section, of arch-shaped brackets secured to the said lower section and extending over and below the sides of the said telescopic section, rollers for the said telescopic section to run on carried by the said brackets, guides having their upper ends secured to the said brackets, supports for the lower ends of the said guides secured to

the said lower section, and slides secured to the said telescopic section and working on the said guides.

6. In a straw-stacker, the combination, 5 with a straw-elevator provided with an upper telescopic section which slides outside of its lower section, of arch-shaped brackets secured to the said lower section and extending over and below the sides of the said 10 telescopic section, rollers for the said telescopic section to run on carried by the said brackets, tubular guides having their upper ends secured to the said brackets, supports for the lower ends of the said guides secured 15 to the said lower section, sprocket-wheels carried by the said lower section, drive-

chains engaging with the said sprocket-wheels and secured to the said telescopic section and having their lower bights arranged in the said tubular guides, a driving-shaft 20 extending across the said elevator and connecting two of the said sprocket-wheels, and slides secured to the said telescopic section and working on the said guides.

In testimony whereof we affix our signatures, in presence of two witnesses.
